[57] CLAIM

The ornamental design for a traffic signal glove, as shown and described.

DESCRIPTION

FIG. 1 is a front elevational view of a first embodiment of a glove showing my new design. The stop sign in the figure is lined for the color red;

FIG. 2 is a rear elevational view of the first embodiment;

FIG. 3 is an elevational view of one side of the first embodiment;

FIG. 4 is an elevational view of the opposite side of the first embodiment;

FIG. 5 is a front elevational view of a second embodiment of a glove showing my new design. The stop sign in the figure is lined for the color red;

FIG. 6 is an elevational view of one side of the second embodiment. The figure is lined for the color yellow;

FIG. 7 is a rear elevational view of the second embodiment. The figure is lined for the color yellow; and,

FIG. 8 is an elevational view of the opposite side of the second embodiment. The figure is lined for the color yellow.
